UNITED STATES PATENT OFFICE.

CALEB C. WALWORTH AND HERMAN SEYTER, OF BOSTON, MASSACHUSETTS.

GEARING FOR OPERATING APPARATUS FOR MIXING AERIFORM FLUIDS.

SPECIFICATION forming part of Letters Patent No. 413,744, dated October 29, 1889.

Application filed October 22, 1888. Serial No. 288,796. (No model.)

To all whom it may concern:

Be it known that we, CALEB C. WALWORTH and HERMAN SEYTER, of Boston, in the county of Suffolk and State of Massachusetts, have 5 invented a new and useful Improvement in Gearing for Operating Apparatus for Mixing Aeriform Fluids, which will, in connection with the accompanying drawings, be herein-after fully described, and specifically defined 10 in the appended claims.

Figure 1 is a top plan view of an apparatus embodying our invention. Fig. 2 is a front elevation of the apparatus shown in Fig. 1. Fig. 3 is a detached sectional view showing 15 the device employed to interlock the pinions with their actuating-shaft. Fig. 4 is a transverse section through the parts shown in Fig. 3. Fig. 5 is a front elevation of one of the pinions shown in the other views.

20 This invention relates to and is an improvement upon the apparatus shown in United States Letters Patent No. 322,661, issued to us on the 21st day of July, 1885, to which patent reference is to be had; and it 25 consists in means whereby the relative velocity of rotation of the two meter-wheels may be differentiated to the necessary degree during all the stages of exhausting the illuminating properties from the fluid in the 30 carburetor, in order that the requisite ratio or proportion of said properties and air may at all times be introduced into the mixer by said wheels to produce a fluid of the requisite illuminating power; and the invention 35 consists in features of novelty hereinafter described, and pointed out in the claims.

Owing to the fact that the hydrocarbon fluid, when first placed in the buried tank or "carburetor," as it is termed, is very rich in 40 hydrocarbon, and that said fluid constantly parts with the same when the apparatus is in use, thus necessitating very frequent but slight changes in the proportions in which the fluid from the carburetor and the air 45 shall enter the mixer, and as such changes are effected by differentiating the relative rotation of the vapor and air meter wheels, therefore it is necessary that they be provided with such connecting-gears as that 50 said changes may be made in an expeditious and convenient manner and in slight de- grees.

In our said former patent one of the meter-wheels was at all times driven at a fixed velocity relative to the connecting-shaft, 55 while the other wheel could at will be differentiated in its rotation relative to both the coacting wheel and said shaft; but such means of effecting said changes is insufficient. Nor is it practical to provide a single gear having 60 a sufficient number of circles of teeth to directly effect the numerous requisite changes; hence we have not only provided means by which to differentiate the rotation of both 65 wheels relative to the connecting-shaft, but the gears employed for this purpose are so constructed that several changes in the relative rotary movement of the wheels may be made for each circle of gear-teeth that are arranged upon the gears carried by said meter-wheels, as will be explained. 70

Referring again to said drawings, A represents one end of a casing or chamber, in which is located a vapor-meter wheel. (Not shown.)

B indicates the end of the chamber or casing, within which is a wheel connected with an air-supply.

C designates the center of the casing, in which the mixing is accomplished.

D represents a frame which supports the meter-wheels, and upon it the mixer is constructed. A tubular conduit is shown at a, by which communication is made between a carburetor and said vapor-meter wheel 85 through its hollow arbor and a stuffing-box, in an old and well-known manner. An arbor c, projecting from the opposite side of said meter-wheel, carries the manifold or multiple crown-gear e. A tubular conduit is shown at 90 b, by which communication is made between an air-supply and said air-wheel through its hollow arbor and a stuffing-box, in an old and well-known manner. An arbor d, projecting from the opposite end of said air-wheel, carries the manifold or multiple crown-gear f. The connecting-shaft is shown at g, mounted in journal-boxes i, pivoted in hangers h, secured to frame D, and upon said shaft the pinions j, having hubs k, are arranged to fit 100 closely, but slide freely, they being adjustably interlocked therewith by means of rings n, formed with an interior diameter greater than the external diameter of said hubs, and hav-

ing a rigid pin *p*, secured in each said ring, extending through hub *k*, and having a coiled spring *q* mounted upon it, a recess being formed in the hub, as shown, of such depth 5 that the spring may be readily compressed therein, while in said ring opposite to pin *p* is rigidly secured a pin *s*, adapted to enter holes *u* in the shaft.

- In Fig. 3 the pinion is shown as locked in 10 position upon the shaft, and to change its position pressure is applied to the ring at pin *p*, thus compressing spring *q* and forcing pin *s* out of hole *u*, (the pin entering slot *t* in the shaft for that purpose only,) when the pinion 15 may be moved on the shaft to the desired point and again interlocked therewith by releasing the ring and allowing the spring to act thereon, thus forcing pin *s* into the intended hole *u*.
- 20 Gears *e f* are each shown as formed with six circles of pin-like teeth, thus constituting a multiple crown gear-wheel, the outer row being formed upon the outer face of peripheral flange *v*, that is formed at right angles 25 to the plane of the wheels, while the pinions are each formed with peripheral teeth *l*, adapted to engage the teeth in circles 2 3 4 5 6, as shown at *e*, Figs. 1 and 2, and with interior teeth *m* upon their end or plane to engage circle 1, as shown at wheel *f*, Figs. 1 and 2.

In carrying our invention into practical effect we preferably employ the following number of teeth in the several circles on wheels 35 *e f*, to wit: circle 1, eighty teeth; circle 2, sixty-four teeth; circle 3, forty-eight teeth; circle 4, thirty-six teeth; circle 5, twenty-four teeth, and circle 6, sixteen teeth; while in pinions *j* there are sixteen peripheral teeth 40 *l* and ten interior teeth *m*, which latter render the eighty teeth in circle 1 of the crown-wheels *e f* equal to one hundred and twenty-eight teeth when used with a sixteen-tooth pinion. As a result of such construction and 45 proportions of the gears, while there are but six changes in each pair of gears, yet we effect twenty-three changes in the relative proportions of air and hydrocarbon delivered, respectively, from the generator and air-supply 50 into the mixer, such changes commencing with eighty-nine per cent. of air and eleven per cent. of fluid from the carburetor and terminating at the other extreme with eleven

per cent. of air and eighty-nine per cent. from the carburetor. In none of said changes is 55 the reduction of air more than seven per cent. and the average is less than four per cent., thus showing that the reduction in air admitted and the increase in fluid admitted from the carburetor is so gradual that the 60 richness in hydrocarbon of the fluid passing from the mixer for illuminating purposes can be very closely graduated, thus insuring the desired result.

As the method of causing the rotation of 65 the meter-wheels, as also the requisite conduits from the air-supply and carburetor to said wheels, are old, common, and well known, it is not deemed necessary to show the same.

We claim as our invention—

1. The combination, with arbors *c* and *d*, arranged to operate the wheels of a gas and air meter, of multiple crown-wheels *e f*, secured to the arbors *c* and *d*, respectively, and the coacting pinions *j*, arranged upon a common shaft and provided with locking and releasing devices, whereby they may be 75 engaged with the several series or circles of teeth in their respective crown-wheels, substantially as specified.

2. The combination, with arbors *c* and *d*, arranged to operate the wheels of a gas and air mixing meter, of multiple crown-wheels *e f*, secured to the arbors *c* and *d*, respectively, and formed with a series of internal circles 85 of teeth, and a peripheral flange *v*, having teeth thereon projecting beyond the plane of the interior teeth, and pinions *j*, mounted upon a common shaft and formed with peripheral teeth *l* and a circle of interior teeth 90 *m*, all substantially as specified.

3. The combination, with arbors *c* and *d*, arranged to operate the wheels of a gas and air mixing meter, of multiple crown-wheels *e f*, secured to the arbors *c* and *d*, respectively, 95 and pinions *j*, mounted on shaft *g*, formed with longitudinal slot *t* and duly-spaced holes *u*, rings *n*, their pins *p* and *s*, and spring *q*, all constructed and arranged to operate substantially as specified.

CALEB C. WALWORTH.
HERMAN SEYTER.
